FUNGICIDAL COMPOSITIONS AND METHODS

Harry A. Sidles, Wheaton, Ill., assignor to Velsicol Chemical Corporation, Chicago, Ill., a corporation of Illinois

No Drawing. Filed Aug. 9, 1965, Ser. No. 478,431
15 Claims. (Cl. 167—39)

This invention relates to new fumigant compositions having high residual activity. In particular this invention relates to compositions containing methyl bromide and insecticidally and fungicidally active materials and a method of applying them to the soil. Methyl bromide has been known for many years to be an extremely effective fumigant. It is extremely effective against a variety of insects, nematodes, weeds and fungi. It is used to fumigate warehouses, plants, mills and other buildings. It is particularly used to fumigate bulk grain. In addition it can be used as a soil fumigant.

While methyl bromide is extremely effective as a fumigant and it gives relatively instantaneous results because it is a gas at normal room temperatures and pressures, it does not have appreciable residual activity. Thus, while it does give an excellent short-term protection against insects, weeds, fungi, it is relatively poor for protecting areas for long periods of time.

It is, therefore, an object of the present invention to provide an effective fumigant having improved residual effect.

It is a further object of the present invention to provide short-term and residual protection against pests and undesirable plant life in a single application.

It is still another object of the present invention to provide compositions that will provide this short and long-term protection without the need for extensive amounts of inert carrier material.

It is still another object of the present invention to provide compositions which will give the desired protection on a uniform basis.

It is still another object of the present invention to devise a method for protecting plants from infestation and infection for a substantial time interval by a single application.

Other objects of the present invention will become apparent from the ensuing description.

It has now been found that compositions containing a major amount of methyl bromide and in addition containing a residual insecticide and a residual fungicide can be easily prepared. These compositions comprising the present invention contain as their active components methyl bromide in combination with residual fungicides and residual insecticides. Since methyl bromide is an odorless and somewhat hazardous material, it is normal to include in compositions containing it a warning agent. One of the most widely used warning agents is chloropicrin. This warning agent is normally present in amounts of about 1 or 2% by weight of the methyl bromide. Other warning agents can be used.

The ratio of the three active ingredients present in the compositions will vary with their identity and with the application for which the composition is being prepared. The reason for this is that various insecticides and fungicides will have different effectiveness and accordingly will require varied amounts to provide adequate protection.

Among the insecticides which can be used in these compositions are the chlorinated hydrocarbons including chlordane, heptachlor, aldrin, and dieldrin. Other insecticides are also useful for specific purposes.

A variety of fungicidally active materials can be used in these compositions. As in the case with the insecticides, their selection will depend upon the material being protected. Among the fungicidally active materials useful

2

are the mercurial fungicides such as mercuric chloride, mercurous chloride, N-methylmercuri-1,2,3,6-tetrahydro-3,6 - endomethano - 3,4,5,6,7,7 - hexachlorophthalimide, N - ethylmercuri - 1,2,3,6-tetrahydro-3,6-endomethano-3,5,6,7,7 - hexachlorophthalimide, N - phenylmercuri-1,2,3,6 - tetrahydro - 3,6 - endomethano - 3,4,5,6,7,7-hexachlorophthalimide, N - (ethylmercuri)-p-toluenesulfonanilide, methylmercuric dicyandiamide, phenylmercury urea, phenylmercuric acetate and hydroxymercurichlorophenol; pentachloronitrobenzene; dithiocarbamate fungicides such as diammmonium ethylenebisdithiocarbamate, ferric dimethyl dithiocarbamate, manganese ethylenebisdithiocarbamate, disodium ethylenebisdithiocarbamate, sodium N - methyldithiocarbamate, zinc ethylenebisdithiocarbamate and zinc dimethyldithiocarbamate; organic copper fungicides such as: copper 8-hydroxyquinolinate, and copper naphthenate; and N-trichloromethylmercapto-4-cyclohexene-1,2-dicarboximide.

In selecting the insecticidal and fungicidal components of the present compositions it is important that they possess appreciable residual activity. This is true of most commercial insecticides and fungicides particularly those indicated above.

The amounts of the specific components of the present compositions as indicated above will vary appreciably depending upon the ultimate use of the composition. It must be kept in mind that in the present compositions different amounts of the methyl bromide, insecticide and fungicide are required for a given application and since all are being applied in a single application, the ratios of the components must be selected in accordance with the amounts of materials required to be applied to the area. For most applications the composition can contain fungicide in an amount by weight of from about 0.05 to 10% of the methyl bromide content. The insecticidal component can also be present in an amount by weight from about 0.05 to 10% by weight of the methyl bromide. For most applications the content of the insecticidal and fungicidal component can be from about 0.1 to 5% by weight of the methyl bromide. The organic mercurial fungicides need be present in many applications in relatively low concentrations. Normally it is sufficient that it be present in an amount from about 0.1 to 1% by weight of the methyl bromide.

Since methyl bromide is a gas at normal temperatures, it is applied from pressure containers. Procedures used for preparing methyl bromide containers can be used in preparing the present formulations. This can be readily accomplished by lowering the methyl bromide to a temperature whereat it is a liquid. Temperatures of from about -10 to -20° C. are adequate.

Once the methyl bromide is in the liquid form the other components of the compositions can be readily dispersed in it. These components would of course include the insecticidally active material, the fungicidally active material and the warning agent such as chloropicrin. This solution is then placed in a suitable container from which it can be discharged as a vapor. It can be seen from this that by using the present compositions there is no need for inert diluent. The methyl bromide in fact acts as a diluent and dispersant for the other components. This eliminates the use of inactive components and maximizes the use of the available container space.

In certain instances it is advantageous to utilize a solvent for the residual fungicide and/or the residual insecticide. The use of this solvent can be of value in improving the uniform application of materials having low solubility in methyl bromide. It is not required by the present invention that these solvents be employed and it is a preferred feature of this invention that they not be present. When an auxiliary solvent is used it preferably

3

will constitute a small percentage of the total composition, although larger amounts can be used.

The selection of the solvent will vary with the identity of the fungicide and insecticide. Compounds known to be useful solvents for these materials can be employed for this purpose. Exemplary of these solvents are the higher boiling alcohols, such as diacetone alcohol and carbitol; mineral spirits; and aromatic solvents, such as benzene, toluene, etc. which are particularly useful for the organic mercurial fungicides, the aromatic solvents also being useful in preparing solutions of pentachloronitrobenzene, the organic copper fungicides and the chlorinated hydrocarbon insecticides.

It has also been found that unusually uniform application of the components is obtained from these formulations. The release of the methyl bromide from the container disperses with it the other components in uniform amounts over the protected area. This uniformity is not easily obtained by other means, particularly by a single application.

Applications of these formulations possess residual activity not possessed by methyl bromide alone. Accordingly, areas treated with this formulation have superior plant growth over a substantial period of time. It has also been found that these formulations remain in the upper layers of the soil where they are best able to protect the area from infestation. Soils treated with the present combination showed larger plants, more plants and a greener color plant than areas treated with methyl bromide alone.

Many formulations can be used by the foregoing procedure and as are illustrated by the following examples:

Example 1

Chlordane (4.5 g.), N-methylmercuri-1,2,3,6-tetrahydro - 3,6-endomethano-3,4,5,6,7,7-hexachlorophthalimide [1.1 g. in diacetone alcohol (6.6 g.)] and chloropicrin (4.5 g.) were placed in a pressure container with a gas outlet. Methyl bromide (437 g.) was cooled to -10° C. and placed in the can. The container was sealed.

The following compositions can be prepared using the procedure of Example 1.

Example 2

Components:	Parts by wt.
N - methylmercuri-1,2,3,6-tetrahydro-3,6-endomethano - 3,4,5,6,7,7 - hexachlorophthalimide	0.25
Heptachlor	0.50
Chloropicrin	1.00
Methyl bromide	98.25

Example 3

Components:	Parts by wt.
N - methylmercuri-1,2,3,6-tetrahydro-3,6-endomethano - 3,4,5,6,7,7 - hexachlorophthalimide	0.25
Aldrin	0.50
Chloropicrin	1.00
Methyl bromide	98.25

Example 4

Components:	Parts by wt.
N - methylmercuri-1,2,3,6-tetrahydro-3,6-endomethano - 3,4,5,6,7,7 - hexachlorophthalimide	0.25
Dieldrin	0.50
Chloropicrin	1.00
Methyl bromide	98.25

4
Example 5

Components:	Parts by wt.
Pentachloronitrobenzene	2.00
Chlordane	1.00
Chloropicrin	1.00
Methyl bromide	96.00

Example 6

Components:	Parts by wt.
Pentachloronitrobenzene	2.00
Heptachlor	0.50
Chloropicrin	1.00
Methyl bromide	96.50

Example 7

Components:	Parts by wt.
Pentachloronitrobenzene	2.00
Aldrin	0.50
Chloropicrin	1.00
Methyl bromide	96.50

Example 8

Components:	Parts by wt.
Pentachloronitrobenzene	2.00
Dieldrin	0.50
Chloropicrin	1.00
Methyl bromide	96.50

Example 9

Components:	Parts by wt.
N-trichloromethylmercapto-4-cyclohexene-1,2-dicarboximide	1.00
Chlordane	1.00
Chloropicrin	1.00
Methyl bromide	97.00

Example 10

Components:	Parts by wt.
Zinc ethylenebisdithiocarbamate	1.00
Heptachlor	0.50
Chloropicrin	1.00
Methyl bromide	97.50

Example 11

Components:	Parts by wt.
N - methylmercuri-1,2,3,6-tetrahydro-3,6-endomethano - 3,4,5,6,7,7 - hexachlorophthalimide	0.05
Chlordane	1.50
Chloropicrin	1.00
Methyl bromide	97.45

Example 12

Components:	Parts by wt.
N - ethylmercuri - 1,2,3,6-tetrahydro-3,6-endomethano - 3,4,5,6,7,7 - hexachlorophthalimide	0.50
Chlordane	0.05
Chloropicrin	1.50
Methyl bromide	97.95

Example 13

Components:	Parts by wt.
Manganese ethylenebisdithiocarbamate	0.10
Aldrin	1.20
Chloropicrin	1.60
Methyl bromide	97.10

Example 14

Components:	Parts by wt.
Ferric dimethyl dithiocarbamate	0.05
Heptachlor	9.00
Chloropicrin	1.00
Methyl bromide	89.95

5
Example 15

Components:	Parts by wt.
Disodium ethylenebisdithiocarbamate	8.00
Aldrin	2.50
Chloropicrin	1.50
Methyl bromide	88.00

It can be seen from this that a variety of compositions of varied amounts of components can be prepared in accordance with the present invention.

While the present compositions are useful in protecting a variety of areas, one of its more important uses is in the protection of tobacco seed beds. Tobacco seed beds are areas where tobacco seedlings are grown for transplanting into tobacco fields. These seedlings are quite open to attack by a variety of pests. It has been found that the present compositions are particularly advantageous in providing this protection. Protection of other seedlings for transplanting can also be accomplished by use of these compositions.

I claim:

1. A composition which consists substantially of methyl bromide, residual fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

2. A composition which consists substantially of methyl bromide, residual mercurial fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

3. A composition which consists substantially of methyl bromide, residual dithiocarbamate fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

4. A new composition which consists substantially of methyl bromide, N-methylmercuri-1,2,3,6-tetrahydro-3,6-endomethano-3,4,5,6,7,7-hexachlorophthalimide in a content of about 0.05 to 10% by weight of methyl bromide and chlordane in a content of about 0.05 to 10% by weight of methyl bromide.

5. A new composition which consists substantially of methyl bromide, N-ethylmercuri-1,2,3,6-tetrahydro-3,6-endomethano-3,4,5,6,7,7-hexachlorophthalimide in a content of about 0.05 to 10% by weight of methyl bromide and chlordane in a content of about 0.05 to 10% by weight of methyl bromide.

6. A composition which consists substantially of methyl bromide, pentachloronitrobenzene in a content of about 0.05 to 10% by weight of methyl bromide and a residual chlorinated insecticide selected from the group consisting of chlordane, heptachlor, aldrin and dieldrin in a content of about 0.05 to 10% by weight of methyl bromide.

7. A method for the protection of plants against infestation and infection which comprises applying to the soil of the plants an effective amount of the composition of claim 6.

8. A composition which consists substantially of methyl bromide, N-methylmercuri-1,2,3,6-tetrahydro-3,6-endomethano-3,4,5,6,7,7-hexachlorophthalimide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

9. A composition which consists substantially of methyl bromide, residual organic copper fungicide in a con-

6

tent of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

10. A composition which consists substantially of methyl bromide, N-trichloromethylmercapto-4-cyclohexene-1,2-dicarboximide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

11. A method for the protection of plants against infestation and infection which comprises applying to the soil of the plants an effective amount of a composition comprising methyl bromide, residual fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

12. A method for the protection of plants against infestation and infection which comprises applying to the soil of the plants an effective amount of a composition comprising methyl bromide, residual mercurial fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

13. A method for the protection of plants against infestation and infection which comprises applying to the soil of the plants an effective amount of a composition comprising methyl bromide, N-methylmercuri-1,2,3,6-tetrahydro-3,6-endomethano-3,4,5,6,7,7-hexachlorophthalimide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.

14. A method for the protection of plants against infestation and infection which comprises applying to the soil of the plants an effective amount of a composition comprising methyl bromide, residual dithiocarbamate fungicide in a content of about 0.05 to 10% by weight of methyl bromide and residual chlorinated hydrocarbon insecticide selected from the group consisting of chlordane, heptachlor, aldrin and dieldrin in a content of about 0.05 to 10% by weight of methyl bromide.

15. A method for the protection of plants against infestation and infection which comprises applying to the soil of the plants an effective amount of a composition comprising methyl bromide, residual organic copper fungicide in a content of about 0.05 to 10% by weight of methyl bromide and a residual chlorinated hydrocarbon insecticide selected from the group consisting of chlordane, heptachlor, aldrin and dieldrin in a content of about 0.05 to 10% by weight of methyl bromide.
